UNITED STATES PATENT OFFICE

HARRY W. GANG, OF HUNTINGTON, WEST VIRGINIA

AUTOMATIC FEED-WATER REGULATOR

Application filed March 5, 1926. Serial No. 92,523.

This invention relates to an automatic water control for steam boilers, the general object of the invention being to provide an expansion tube acted upon by the steam in the boiler to cause it to expand to open a valve which supplies steam to the water inspirator so that water will be supplied to the boiler, with means for permitting some of this water to act on the expansion tube, 10 when the water reaches a certain level, which will cause the tube to contract and thus close the valve and stop the operation of the inspirator.

This invention also consists in certain 15 other features of construction and in the combination and arrangement of the several parts, to be hereinafter fully described, illustrated in the accompanying drawings and specifically pointed out in the appended 20 claim.

In describing my invention in detail, reference will be had to the accompanying drawings wherein like characters denote like or corresponding parts throughout the several views, and in which:—

Figure 1 is an elevation of the device.

Figure 2 is a plan view of portion of the device.

Figure 3 is a section on line 3—3 of Figure 2.

Figure 4 is a diagrammatic view showing means for connecting the device to the inspirator and to its overflow valve.

Figure 5 is a section on line 5—5 of Figure 4.

Figure 6 is a section on line 6—6 of Figure 4.

In these views, 1 indicates the expansion tube which is supported at one end by the 40 support 2 and said tube passes through an opening formed in the support 3 of the valve chest 4. The free end of the tube is closed by the cap 5 which carries a rod 6 which is connected to a lever 7 by a clip 8. Said 45 lever is connected by the rod 9 and clip 10 to the valve 11 in the chest 4. The chest is provided with the central exhaust port 12 which leads to the exhaust pipe 13 and with the ports 15 and 16 which are connected by 50 the pipes 17 and 18 with opposite ends of the

cylinder 19, the piston of which is connected by the rod 20 with the water inspirator or other pumping device for feeding water to the boiler. Steam is delivered to the valve chest through means of the pipe 21 and the lubricator for the valve chest is shown at 22. A pipe 23 connects the tube 1 to a steam space of the boiler and a pipe 24 connects the free end of the tube 1 with the boiler, below the lowest water level thereof. As will be seen, the support 2 is provided with a threaded socket to receive the threaded end of the tube 1 and the upper end of the support is provided with a threaded hole which communicates with the tube 1 and receives the lower end of the pipe 23. The tube 1 is held at a one inch slope, and this tube must be placed at the level where it is desired to hold the water in the boiler.

The rod 20 of the piston in cylinder 19 has an extension 25 pivoted thereto which operates in a cylinder 26 which in turn is connected by a link 27 with an inspirator, a part of which is shown at 28. The extension 25 has a certain amount of free movement relative to the cylinder 26 through means of the nuts 29 and 30 thereon and which are arranged at each side of the top of the cylinder so that the rod 20 and the extension 25 can move in either direction to a certain extent at the beginning of each stroke without moving the cylinder, but as soon as one of the nuts engages the cylinder, the cylinder will be caused to move with the extension. A spring 31 is arranged in the cylinder to absorb shocks.

In order to open the overflow valve 32 of the inspirator by the device, I pivot a link 33 to an upright 34 carried by the cylinder 19, the other end of the link being pivoted to a link 35 and a link 36, the link 35 being pivoted to a collar 37 on the rod 20, while the link 36 is pivoted to a bell crank 38 which is connected with the valve 32 by the link 39. Thus the valve 32 will be opened and closed on the reciprocation of the rod 20 by the piston in the cylinder 19.

When the water in the boiler drops below a level where it will flow from the tube 1, steam will enter the tube through the pipe

23 and this steam will cause the tube to expand so that it will move the lever 7 and therefore the valve 11 to a position where the ports 15 and 12 will be connected together so that the rear end of cylinder 19 will be opened to exhaust and live steam will pass through port 16 and pipe 18 into the front end of the cylinder 19, which will move the inspirator to operative position 10 and thus feed water into the boiler. At the same time, the overflow valve of the inspirator will be opened. The water will continue to rise in the boiler until it reaches a level where it will flow into the tube 1 from the pipe 24 and this comparatively cool water will act to cause the tube to contract, so that the lever 7 and valve 11 will be moved to their other position and thus stop the feeding of water to the boiler. Thus 15 the device is entirely automatic and will 20 keep the water in the boiler at a certain level.

It is thought from the foregoing description that the advantages and novel features 25 of my invention will be readily apparent.

I desire it to be understood that I may make changes in the construction and in the combination and arrangement of the several parts, provided that such changes fall 30 within the scope of the appended claim.

What I claim is:—

A feed water regulator for boilers comprising an expansible tube, a stationary support for one end of the tube, said support 25 having a threaded socket therein for receiving the end of the tube and said support having a threaded hole in communication with the tube, a pipe extending into said hole and adapted to connect to the steam space 40 of a boiler, a second support having an opening therein through which the tube passes, the opening being below the plane of the point of attachment of the tube with the first support so that one end of the tube is 45 lower than the other end thereof, a cap closing the low end of the tube, a pipe adapted to connect the low end of the tube with the water space of a boiler, said pipe being connected with the cap, a steam chest on the 50 second support, a slide valve therein for controlling the flow of steam to a water feeding device, a lever pivoted to a stationary part at its lower end, a stem connected with the valve and pivotally connected with the upper end of the lever and a rod connecting the cap on the low end of the tube with the lever so that the expansion and contraction of the tube will operate the lever.

60 In testimony whereof I affix my signature.

HARRY W. GANG.
